UNITED STATES PATENT OFFICE.

CARL R. HOUGHTON, OF CONNERSVILLE, INDIANA, ASSIGNOR TO THE CONNERSVILLE BLOWER CO., OF CONNERSVILLE, INDIANA, A CORPORATION OF INDIANA.

GAS-EXHAUSTER GOVERNOR.

Application filed September 9, 1921. Serial No. 499,491.

To all whom it may concern:

Be it known that I, CARL R. HOUGHTON, a citizen of the United States, residing at Connersville, in the county of Fayette and State of Indiana, have invented a new and useful Gas-Exhauster Governor, of which the following is a specification.

In the operation of gas plants or by-product coke plants, it is desirable to maintain a constant suction in the gas suction main which leads to the exhauster. The quantity of gas which passes through the exhauster is nearly constant over long periods. The variation in the speed of the exhauster in a day's run is ordinarily less than 10% from minimum to maximum. The variation of speed within an hour is ordinarily less than 5%. The variation in a five-minute period is ordinarily less than 1% to correct for the variation in the quantity of gas.

Since the exhauster must run at a nearly constant speed, and yet must be able to change its speed promptly to correspond with changes in the quantity of gas supplied, the question of regulation is extremely important; for any material variation in the pressure in the gas suction main is not permissible. While it would seem that the problem of obtaining this regulation is very simple, especially in view of the relatively constant rate at which gas is supplied to the exhauster, yet as a matter of fact it is found very difficult so to regulate the speed of the exhauster that the pressure within the gas suction main is maintained within the proper limits. If a pressure governor alone is used to balance the gas-exhauster speed against the suction in the gas suction main, a slight variation in the steam pressure causes the exhauster to change its speed, and this in turn changes the suction in the gas suction main, which change again in turn is transmitted to the governor and back to the engine; with the result that ordinarily there is a continual swinging, surging, or hunting action, with the pressure and the speed alternately rising materially above and falling materially below the desired pressure and speed, instead of remaining substantially constant.

It is the object of my invention to correct for variation in the steam pressure and other disturbing factors before the change in the exhauster speed can effect the pressure in the gas suction main, and thus to avoid

the surging or hunting effect referred to above.

In obtaining this result, I use a small rotary blower, preferably a positive-pressure blower, which is driven from the exhauster at a speed proportional to that of the exhauster, and use the pressure from this blower to govern the engine speed, preferably jointly with a pressure governor responsive to the pressure in the gas suction main.

The accompanying drawing illustrates my invention: Fig. 1 is a side elevation of an exhauster and governor embodying my invention, some of the parts of the governor being shown in section; and Fig. 2 is a central vertical section through the pilot valve which is operated by the pressure governor.

The exhauster 10 is driven by the usual engine 11, or other driving means, and draws gas from the usual gas suction main 12 and discharges it into the usual discharge main 13, which two mains are connected to the collecting mains of the oven batteries and to the usual gas-handling means of a gas plant in the well understood way.

The steam for the engine 11 is supplied through a pipe 14, and the supply of steam is controlled by a lever 15, which may be any suitable control lever for any desired kind of engine control. The lever 15 is operable by an arm 16 provided with a counterweight 17; and the arm 16 is connected to the piston rod 18 of a piston 19 movable vertically in a cylinder 20 so that when the piston 19 rises the arm 16 works the lever 15 to reduce the engine speed and vice versa. The cylinder 20 together with its piston 19 and the connection 18 and lever 16 constitute a pressure responsive device connected to the control member of the engine for controlling the steam supply thereto. For the sake of safety, I also provide a ball governor 21, responsive to the engine speed, but this ball governor is arranged to come into play only when the speed of the exhauster rises unduly high, so that it plays no part in the regular controlling action and is merely a safety device.

The lower part of the cylinder 20 is connected to an air-supply pipe 25 and to an air-outlet pipe 26, both of which communicate with the cylinder 20 below the lowest point which the piston 19 can reach. The

air-supply pipe 25 is connected to the outlet of a small blower 27, preferably a rotary positive-pressure blower, which is driven in any suitable manner from the exhauster 10 so that the speed of the blower and of the exhauster vary in proportion; as shown, the driving of the blower 27 is by an ordinary belt 28, but this is merely one illustration. Thus as the speed of the exhauster 10 increases, the speed of and consequently the quantity of air discharged by the blower 27 is proportionately increased. The air-outlet pipe 26 leads from the cylinder 20 to a pilot valve 29, which is shown in detail in Fig. 2. This pilot valve is a continuous-leakage valve, the amount of the leakage depending upon the position of the valve stem 30. This valve stem 30 projects through the end walls of a chamber 31 into which the pipe 26 leads, and the stem is provided at such end walls with cut-away portions 32 which allow the escape of air from the chamber 31 at a rate dependent upon the position of the stem 30. The cut-away portions 32 are so arranged that a balance of the leakage air through the two end walls is obtained, and the stem thereby maintained in a balanced condition.

The stem 30 of the pilot valve is connected by a link 35 to a lever 36, provided with arc-shaped ends to get constant lengths of effective lever arms. The float 37 of the gasometer hangs from one end of the lever 36, and a counterweight from the other. The float 37 is vertically movable, as a gasometer float, in an open-topped water container 39 of the gasometer, and a pipe 40 which communicates with the gas suction main 12 opens beneath the float 37, so that the pressure beneath such float is that existing within the gas suction main. It is thus seen that the container 39 together with its float 37 constitute a pressure responsive device responsive to the pressure in the gas main for controlling the operation of the leakage or pilot valve 29.

In operation, the exhauster 10 draws gas from the gas suction main 12 and discharges it into the discharge main 13. The blower 27 blows air through the pipe 25 into the cylinder 20 beneath the piston 19, and more or less of the air thus supplied to the cylinder 20 escapes therefrom through the pipe 26 and pilot valve 29, the amount escaping depending upon the position of the stem 30 of the pilot valve. The air pressure beneath the piston 19 raises such piston to a greater or less height, and thus moves the control lever 15 more or less. The blower 27 keeps a constant pressure on the bottom of the piston 19 for a constant speed of the exhauster. If for any reason the speed of the exhauster increases, as because of a change in steam pressure or because of a change due to a movement of the float 37

as hereinafter described, the speed of the blower changes correspondingly, and the pressure beneath the piston 19 is instantly correspondingly increased. This increased pressure raises the piston 19, and moves the control lever 15 in the proper direction to produce slowing down of the engine until the pressure beneath the piston 19 is the same as it was before, (though the piston may be in a different position from what it was at first,) which return of the pressure beneath the piston to its original value does not occur until the speed of the blower 27, and therefore of the exhauster, is the same as it was before. This gives an instantaneous control and effectually prevents the objectionable surging and hunting.

If the quantity of gas supplied through the gas suction main 12 changes, the pressure in such main correspondingly changes and the gasometer float 37 rises or falls. This movement of the float 37 moves the stem 30 of the pilot valve 29 to allow more or less air to escape at the pilot valve, and such change in the air leakage produces a downward or upward movement of the piston 19 to operate the control lever 15 to increase or decrease the steam supply and thus to make the exhauster 10 and blower 27 run at a greater or less speed to correct for this difference in air leakage and thus to take care of the change in the quantity of gas supplied through the gas suction main 12. The float 37 is preferably provided with a nearly closed bottom 41 so that the water can pass into or out of the float only at a slow rate. This makes the movement of the float 37 relatively sluggish and dead-beat, and this assists in preventing any hunting or surging action. In case the governing action above described fails for any reason, and the speed of the engine and exhauster rises unduly, the ball governor 21 comes into play and prevents the engine from running away.

I claim as my invention:

110

1. In combination, an exhauster drawing gas from the gas suction main and discharging it into the discharge main of a gas plant, an engine for operating said exhauster, a control member controlling the supply of steam to said engine, a pressure-responsive device connected to said control member to operate it, and a blower arranged to operate at a speed proportional to that of the exhauster and supplying air to said pressure-responsive device.

2. In combination, an exhauster drawing gas from the gas suction main and discharging it into the discharge main of a gas plant, an engine for operating said exhauster, a control member controlling a supply of steam to said engine, a pressure-responsive device connected to said control member to operate it, a blower arranged to operate at a speed proportional to that of

115

120

125

130

- the exhauster and supplying air to said pressure-responsive device, and a leakage valve connected to said pressure-responsive device, and a second pressure-responsive device responsive to the pressure in said gas suction main and controlling said leakage valve.
3. In combination, an exhauster drawing gas from the gas suction main and discharging it into the discharge main of a gas plant, driving means for said exhauster, a control member controlling the supply of energy to said driving means, a pressure-responsive device connected to said control member to operate it, and a blower arranged to operate at a speed proportional to that of the exhauster and supplying air to said pressure-responsive device.
4. In combination, an exhauster drawing gas from the gas suction main and discharging it into the discharge main of a gas plant, driving means for said exhauster, a control member controlling the supply of energy to said driving means, a pressure-responsive device connected to said control member to operate it, a blower arranged to operate at a speed proportional to that of the exhauster and supplying air to said pressure-responsive device, and a leakage valve connected to said pressure-responsive device, and a second pressure-responsive device which is responsive to the pressure in said gas suction main and controlling said leakage valve.
5. In combination, an exhauster drawing gas from the gas suction main and discharging it into the discharge main of a gas plant, an engine for operating said exhauster, a control member controlling the supply of steam to said engine, a cylinder and piston, said piston being connected to said control member to operate it, and a blower driven at a speed proportional to the speed of the exhauster and supplying air to said cylinder.
6. In combination, an exhauster drawing gas from the gas suction main and discharging it into the discharge main of a
- gas plant, driving means for said exhauster, a control member controlling the supply of energy to said driving means, a cylinder and piston, said piston being connected to said control member to operate it, and a blower driven at a speed proportional to the speed of the exhauster and supplying air to said cylinder.
7. In combination, an exhauster drawing gas from the gas suction main and discharging it into the discharge main of a gas plant, an engine for operating said exhauster, a control member controlling the supply of steam to said engine, a cylinder and piston, said piston being connected to said control member to operate it, a blower driven at a speed proportional to the speed of the exhauster and supplying air to said cylinder, an outlet pipe from said cylinder, a continuous-leakage pilot valve connected to said outlet pipe and thus controlling leakage from said cylinder, and a gasometer having a float which is subject to the pressure within said gas suction main, said float being operably connected to said pilot valve.
8. In combination, an exhauster drawing gas from the gas suction main and discharging it into the discharge main of a gas plant, driving means for said exhauster, a control member controlling the supply of energy to said driving means, a cylinder and piston, said piston being connected to said control member to operate it, a blower driven at a speed proportional to the speed of the exhauster and supplying air to said cylinder, an outlet pipe from said cylinder, a continuous-leakage pilot valve connected to said outlet pipe and thus controlling leakage from said cylinder, and a gasometer having a float which is subject to the pressure within said gas suction main, said float being operably connected to said pilot valve.

In witness whereof, I have hereunto set my hand at Indianapolis, Indiana, this 1st day of September, A. D. one thousand nine hundred and twenty one.

CARL R. HOUGHTON.
